UNITED STATES PATENT OFFICE.

GEORGE S. HUFF, OF PORTLAND, INDIANA, ASSIGNOR TO SILAS H. ADAMS, OF SAME PLACE, AND EZRA BAKER, OF KALAMAZOO, MICHIGAN.

HAND-OILER.

SPECIFICATION forming part of Letters Patent No. 624,035, dated May 2, 1899.

Application filed July 16, 1898. Serial No. 686,130. (No model.)

To all whom it may concern:

Be it known that I, GEORGE S. HUFF, a citizen of the United States, residing at Portland, in the county of Jay and State of Indiana, have invented certain new and useful Improvements in Oil-Cans; and I do hereby declare the following to be a full, clear, and exact description of the invention, such as will enable others skilled in the art to which it appertains to make and use the same.

This invention relates to an improvement in hand-oilers having a forced feed; and its object is to provide a simple and effective oiler having detachable parts and capable of holding liquid lubricant under strong pneumatic pressure, having effective valves of peculiar construction for retaining said lubricant in its compressed condition for any desired length of time, having a spring ejection-valve positive in action and securely seated by the outward pressure of the contents of the oiler, and having means for adjusting and for obtaining access to said oiler.

To these ends the invention consists in the novel construction and combination of parts hereinafter described and claimed, and illustrated in the accompanying drawings, in which—

Figure 1 is an elevation of the oiler. Fig. 2 is a vertical longitudinal section through the device with stem broken away. Fig. 3 is a central horizontal section through the ejector-valve, and Fig. 4 is a detailed view of the parts of said valve detached.

Referring to said figures by letters of reference, A is the body of the oiler, of any desired material, preferably copper, and is provided with a lower flat bottom *a* and an upper or strengthening bottom *a'*, as shown. Said body is provided near its lower end with a tube B, communicating therewith and secured at its other end to a pump C, thereby creating a direct passage from the pump to the interior of receptacle A. Said tube B is provided near its outer end with a suitable valve *b*, which serves to prevent all backward escape of the compressed liquid within the receptacle.

Pump C projects upward from the tube B and is secured near its upper end to the upper part of the body A by means of a metal

bar or plate B². A piston *c* and rod *c'*, of the ordinary construction, are provided, and a detachable cover C' permits the ready withdrawal of the piston for repairs, &c. While the pump has been shown as permanently fixed to the tube B and rod B², it is obvious that it may, if desired, be detachably secured thereto in any suitable manner.

Within the center of the top of the body portion A is secured a reinforce A', as shown, 60 preferably provided with a flange A², which overlaps the surrounding portion of said top and is preferably soldered thereto. Said reinforce is also provided with an upwardly extending portion *a*², to which is screwed or otherwise secured a valve-casing D, directly communicating with which is a tube E, the upper end of which is likewise secured by means of an air-tight joint to the reinforced center A' of the top of body A, and which projects downward to a point near the bottom of the body or receptacle and preferably on the side thereof farthest from the tube B. Said pipe E is provided with a screen or netting *e*, which serves to strain the lubricant passing 75 therethrough up into the pipe E.

Valve-casing D is preferably substantially cross-shaped in side elevation and is provided with adjacent upper and lower chambers *d'd'*, separated by a central partition *d*², as shown, 80 and communicating through the valve-seat D'. The horizontally-extending cylindrical arms D² D³ of the valve-casing are hollow, and are adapted to receive and guide the valve-rod F. Said rod projects through arm 85 D² and is held in a horizontal position therein by means of a threaded cap f², screwed into the outer end of said arm, and by a side partition f³ at the opposite end thereof. The chamber formed thereby around rod F is 90 preferably filled with suitable packing to prevent the oozing out or leaking of the oil during its passage through the discharge-pipe. Rod F passes through partition d², its valve F' resting in a valve-seat formed in the further side of the partition. Arm D³ projects outward from this point and is adapted to receive the valve when pressed inward, so as to permit the free passage of the fluid through the valve-opening. Said arm is provided with 95 100

a detachable end d^3 , which may be removed if it is desired to obtain access to the valve in order to clean or repair the same. Resting against cap f^2 and encircling rod F, is a coiled spring F², the opposite end of which bears against a collar F³, adjustably secured to said rod F by means of a screw f⁴, as shown. Said spring serves to keep valve F' normally seated.

10 1. A discharge-pipe G of desired construction is screwed or otherwise secured upon the upper end of the valve-casing and communicates directly with the upper chamber d thereof.

15 2. In operation the body A is filled by pouring the lubricant through the opening in the top thereof, which is closed by a screw-cap II. When a desired quantity has been placed therein, the pump-piston is forced up

20 and down, forcing the air into body A through tube B. The air will rise above the liquid, and all backward flow of the fluid is prevented by valve b'. When sufficient pressure with-

25 in body A has thus been obtained, the can is grasped by the pump, which serves as a handle, and a finger is brought to bear upon the knob f⁵ on rod F. Upon pressing the same inward spring f² is compressed and valve F' is removed from its seat. Immedi-

30 ately the pressure of the air forces the oil down and up through the screen e into pipe E, thence to chamber d' through the valve-opening into chamber d and out through the discharge-pipe G. The outflow of the liquid

35 can be readily regulated by the amount of force exerted upon rod F, which immediately reseats itself upon removing all pressure. It will be noticed that all outward pressure of the contents of the body tends to force the

40 valve more tightly against its seat, thus preventing the gradual escape of fluid which occurs in valves which depend upon a spring to overcome the internal pressure.

Another great advantage of this invention 45 is the detachability of all working parts. Whenever it is desired to clean or repair a part of the valve or its casing, it may be readily detached and replaced without causing the slightest trouble. If desired, the

50 pump may also be detachably secured to tube B and rod B² in any suitable manner.

In the foregoing description I have shown the preferred form of my invention; but I do not limit myself thereto, as I am aware 55 that modifications may be made therein without departing from the spirit or sacrificing the advantages thereof, and I therefore re-

serve the right to make such changes as fairly fall within the scope of my invention.

Having thus described my invention, what I therefore claim as new, and desire to secure by Letters Patent thereon, is—

1. In a hand-oiler, the combination of the valve-casing having an upper and a lower chamber separated by a central partition, a valve-rod slidably secured in a horizontal position in said casing by means of a cap and side partition, as shown, packing held between said cap and partition, a valve upon the inner end of said rod adapted to be seated 70 in a valve-seat formed in said central partition, and be opened inwardly, a chamber, for the reception of said opened valve, having a removable cap, for the purpose described, and means for retaining said valve in a normally-closed position, consisting of a coiled spring upon said rod bearing between the cap and a collar adjustably secured to said rod, all substantially as and for the purpose described. 80

2. A hand-oiler consisting of a body having a combined handle and pump communicating therewith by means of an automatic valved tube, an inlet for the reception of oil into said body, a valve-casing detachably secured to the reinforced center of the top of said body, a tube secured to said reinforced center and communicating with said casing, and projecting down into the body, having its lower end screened, as described, an upper and a lower chamber in said valve-casing separated by a central partition, a horizontal valve-rod passing through said central partition and projecting into the lower chamber, a valve upon the inner end of said rod, a valve-seat therefor, a chamber for receiving said valve when open, a detachable cap for said chamber, a cap and a side partition for guiding the valve-rod into its proper position, packing incasing said rod between the cap and side partition, a spring for normally seating the valve and tensioned by means of an adjustable collar on said rod, a button upon the outer end of said rod and adjacent to the handle, and a discharge-tube detachably secured to the valve-casing, all substantially as and for the purpose described. 100

In testimony whereof I affix my signature in presence of two witnesses.

GEORGE S. HUFF.
